Inventor:

William Mc Gie Young
by *Frederick Vaughan & Co* Att'y's

UNITED STATES PATENT OFFICE.

WILLIAM MCGIE YOUNG, OF VICTORIA, BRITISH COLUMBIA, CANADA.

GLASS-WASHER.

1,337,303.

Specification of Letters Patent. **Patented Apr. 20, 1920.**

Application filed April 27, 1916. Serial No. 93,981.

To all whom it may concern:

Be it known that I, WILLIAM MCGIE YOUNG, a subject of the King of Great Britain, and resident of Victoria, in the 5 Province of British Columbia, Dominion of Canada, have invented certain new and useful Improvements in Glass-Washers, of which the following is the specification.

This invention relates to improvements in
washers for glasses, tumblers and other vessels, and the objects of the invention are to enable the glasses to be rapidly washed in a sanitary manner by the continuous application of clean water.

15 The invention is particularly serviceable for washing glasses or tumblers in bars, ice-cream parlors, restaurants or other establishments where the same set of glasses are maintained in use by the public, and it consists essentially of a draining receptacle or sink having a tray around the top of the same, a central water distributing nozzle within the receptacle having orifices through which the water is discharged outwardly

25 and means for directing jets of water on the exterior of the glass at the same time as on the interior, all as hereinafter more fully set forth and described in the accompanying specification and drawing.

Fig. 2 is a top plan view of the same.

Fig. 2 is a top plan view of the same.
Referring to the drawing, 1 represents the tray having a central opening 1^a, from 35 which the draining receptacle or sink 2 extends downwardly. Within is arranged a vertical sprayer 3, and a horizontal sprayer 4 and a mounted rack 7, which is caused to rotate by the force of water from the horizontal sprayer impinging upon it and the glass A. as hereinafter described.

3 represents the vertical nozzle or spraying device. It is simply a hollow nozzle specially shaped and perforated at proper intervals with a plurality of fine orifices through which water is designed to be discharged in a spray against the interior of the tumbler A, which said tumbler is supported on the rack 7. This sprayer may also be equipped with any convenient form of spraying device which will cause a thin curtain of water to be directed around the bottom of the glass.

4 represents the horizontal sprayer which consists of a pipe 5 bent into circular form 55 to which are attached the sprayers or roses 6 set at proper intervals and formed with a plurality of fine orifices through which a spray is caused to impinge on all sides of the exterior of the glass. These roses are set 60 at an angle, off center, Fig. 2, the object being that the force of the water discharging against the glass will cause it to rotate.

7 represents the rack which is supported on the vertical sprayer 3. The base of this rack is mounted on an ordinary ball-bearing race or otherwise, to permit of the rack rotating with a little friction as possible. On the edge of the rack at proper intervals are small projections or fins 8 which will partially take the force of the water from the roses 6, thus causing a rapid rotation of the glass, the effect of which is to provide that the water from the vertical sprayer 3 will more thoroughly wash the interior of the glass. The rack may be designed to permit of glasses of various sizes being washed.

Water, hot or cold as desired, is supplied to the sprayers 3 and 4 by pipes 9 and 10 which are controlled by the valve 11, operated by the handle 12 extending above the table B.

The valve 11 may be of any suitable style such as an ordinary plug cock and may be fitted with a spring that will cause it to close the moment the handle 12 is released.

From the receptacle or sink 2 the waste water may pass to the drain 13.

If desired, the tray and sink or container may be made of glass so that the operation of the device may be readily observed and the sanitary nature thereof shown to the public.

As many changes could be made in the above construction and many apparently widely different embodiments of my invention within the scope of the claim, constructed without departing from the spirit or scope thereof, it is intended that all matters contained in the accompanying specification and drawing shall be interpreted as illustrative and not in a limiting sense. 95 100

What I claim as my invention is:

A device of the class described, comprising a receptacle, an annular water pipe in 105 the receptacle having inwardly disposed

water roses arranged slightly offset, a perforated conical nozzle centrally located in the receptacle, a rotatable flange on the nozzle adapted to receive a glass, fins on the flange, and means whereby water is simultaneously sprayed through the nozzle and the roses to simultaneously clean the inside and outside of the glass, the roses being designed to project the spray tangentially on

the glass and the rack to impinge on the 10 fins, as and for the purpose specified.

In witness whereof I have hereunto set my hand in the presence of two witnesses.

WILLIAM McGIE YOUNG.
